UNITED STATES PATENT OFFICE

HARRY M. BRAMBERY, OF NEWCASTLE, INDIANA, ASSIGNOR TO THE PERFECT CIRCLE COMPANY, OF HAGERSTOWN, INDIANA, A CORPORATION OF INDIANA

PISTON FOR INTERNAL COMBUSTION ENGINES AND THE LIKE

Application filed September 20, 1930. Serial No. 483,186.

This invention relates to pistons for internal combustion engines and the like.

The principal object of the invention is to provide a piston which is especially designed to maintain an efficient and uniform clearance between the skirt portion and the cylinder wall throughout the entire operating temperature range of the engine. More particularly, I provide a piston in which there is approximately ideal functional coordination between the head and the skirt so that the higher thermal expansion of the head will not distort or change the shape of the skirt under operating conditions and the most efficient clearance between the skirt and cylinder is uniformly maintained to obtain improved oil control and eliminate piston slap, blow-by, excessive friction, scoring and excessive wear.

More specifically my invention is an improvement on the so-called Nelson Invar-Strut aluminum piston which is now in extensive commercial use and is of the type illustrated in the Nelson Patents Nos. 1,681,621 and 1,731,904.

Further objects and advantages of my invention will appear from the following description taken in connection with the accompanying drawings in which:

Fig. 1 is a side elevation of a piston embodying my invention;

Fig. 2 is a side elevation taken at 90° to Fig. 1 and showing the piston partly in section as on the line 2—2 of Fig. 1;

Fig. 3 is a bottom plan view of my piston;

Fig. 4 is a vertical section taken on the line 4—4 of Fig. 2;

Fig. 5 is a reduced side elevation of a Nelson Invar-Strut piston and

Fig. 6 is a reduced side elevation of the Nelson piston taken at 90° to Fig. 1 and showing the piston partially in section as on the line 6—6 of Fig. 5.

Referring first to Figs. 5 and 6, the Nelson Invar-Strut piston which is formed of an aluminum alloy comprises a head 7, a skirt 8 consisting of cross-head slippers 9 and a lower circular guide and oil control portion 10, webs 11 depending from the head, provided with piston pin bosses 12 and rigidly connected below the bosses directly to the circular portion 10 by integral portions 13, and Invar-Struts 14 which extend transversely of the webs 11 and connect or tie the adjacent sides of the slippers 9 to the webs 11. The upper ends of the cross-head slippers 9 are separated from the lower edge of the head by circumferential slots 16. The skirt is provided with the vertical slot 17 extending upwardly from the lower edge thereof to near the upper end of one of the cross-head slippers.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

With the Nelson piston, as just described, the diameter across the cross-head slippers 9, is fitted to the cylinder with very close clearance, since the normal expansion of aluminum as the temperature increases, during operation of the engine, is compensated for by the Invar-Struts 14, which are formed of material, such as steel, which is relatively inexpansile as compared with the aluminum alloy. The lower circular portion 10 of the skirt, however, is permitted to expand at the normal rate of aluminum alloy, as this portion is below the Invar-Struts and not materially affected thereby. As the lower ends of the webs 11 are directly and rigidly connected to the circular portion 10 on opposite sides, it will be manifest that as the head expands the outward movement of the webs in opposite directions, expands and distorts the circular position; the expansion of the head being greater than the normal expansion of the skirt because of the greater temperatures to which the head is subject. The additional expansion of the skirt, due to the expansion of the head must be compensated for by the vertical slot 17. The circular portion 10 of the skirt is ordinarily fitted with a closer clearance than advisable in order that the piston will not "slap" when the engine is cold and to obtain better oil control. This close fit, however, results in high friction especially under maximum power and high speed conditions, due largely to the distortion of the skirt portion 10 by the expansion of the head. The vertical slot 17 is made quite long in an attempt to reduce this friction but by increasing the length of the slot, the skirt becomes too flexible for satisfactory cross-head pressures and rocking.

of the piston in the cylinder results with attendant defects in operation. The long slot 17 reduces the strength of the cross-head slipper into which the slot extends to an extent 5 insufficient to withstand the outward movement of the webs 11 and the Invar-Struts, so that the slippers tend to flatten out and their diameter at the slot 17 is reduced. This together with the distortion of the circular 10 portion 10 due to the expansion of the head causes high pressure areas, indicated by the dotted lines 18 and 19 in Fig. 5. As these pressure areas wear the piston becomes loose in the cylinder which results in poor oil control, piston rocking, etc. Fitting the piston still more snugly cannot be employed satisfactorily to overcome this defect, since scoring 15 would result.

I overcome the above mentioned disadvantages by the improvement embodying my invention which I will now describe in connection with Figs. 1 to 4. I have used in these figures, as far as applicable, the same reference numerals employed in the above 20 description to designate corresponding parts, and therefore it will be but necessary now to describe in detail the features of my invention.

It will be observed that the heads, skirts, 25 webs and bosses of the two pistons are very similar in general design, the two most essential differences being that the lower ends of the webs 11 in my piston are integrally connected to flexible arcuate cross struts 20 instead of being directly connected to the 30 upper edges of the circular section 10 as in the Nelson piston, and the slot 17 in my piston is relatively short compared with Nelson's long slot 17. I also prefer to strengthen 35 the upper ends of the slippers 9 by providing internal ridges 22 (Fig. 4). The struts 20, which are cast integral with the piston are oppositely curved and preferably, though not necessarily, the radius of each is larger 40 than that of the piston. They extend transversely of the bosses and are preferably connected at their ends only to the circular portion 10.

The radius struts 20 operate at a slightly 45 higher temperature and expand linearly to a greater degree than the skirt section 10, since the struts 20 are connected to the webs 11 to which heat is transmitted from the high temperature head. As the head expands the accompanying outward movements of the webs 11, axially of the piston pin, are taken up by the radius struts 20 without being transmitted to the lower skirt portion 10, due to the flexing and linear expansion of 50 the radius struts 20. As a result the mechanical distortion of the circular portion of the skirt by reason of the thermal expansion of the head is practically eliminated. The slot 17 may thus be made relatively short 55 so that the portion of the cross-head slipper

above the slot, is relatively stronger and rocking of the piston is eliminated. Since the struts 20 support the circular portion 10, the cross-head way, they strengthen the skirt where the slot 17 tends to weaken it.

It is manifest that since the lower skirt portion of my piston is not distorted by the high expansion of the head and this lower portion and the cross-head slipper, receiving the slot 17, are made relatively stronger, the skirt may have a close and uniform clearance throughout the operating range, resulting in minimum friction, absence of piston slap, excellent oil control and long life. The pressure and clearance being uniform; the lower portion of the skirt properly meters the oil film to the usual oil control ring which is highly desirable.

If desirable, two slots 17, diametrically positioned may be provided in which case the slot-length is still further reduced and they do not extend up so far into the respective cross-head slippers.

I claim:

1. A piston having a head, a skirt comprising a lower circular portion and cross-head slippers separated from the head, webs depending from the head and provided with piston pin bosses between said cross-head slippers, and cross struts connected at their opposite ends to the circular portion and connected to the lower ends of the respective webs, the struts being curved outwardly from their ends toward the adjacent surface of the lower circular portion and of greater radius than that of the piston and the skirt being provided with a slot extending from its lower edge part way into one of said cross-head slippers.

2. A piston having a head, a skirt comprising a lower circular portion and cross-head slippers separated from the head, webs depending from the head and provided with piston pin bosses between said cross-head slippers, flexible arcuate cross struts within and connected at their ends to the circular portion and connected to the lower ends of said webs, the skirt being provided with a slot extending from its lower edge into one of said cross-head slippers, and relatively inexpandable cross struts between the webs and the cross-head slippers on each side of the piston.

3. A piston having a head, a skirt comprising a lower circular portion and upwardly extending cross-head slippers separated at their upper ends from the head, the skirt being provided with a slot extending from its lower edge into one of said cross-head slippers, webs depending from said head and spaced from said skirt, piston pin bosses on said webs, outwardly curved flexible struts having a radius greater than that of the piston and having their ends integral with the circular portion, the distance between the adjacent ends of the struts being less than

the length of the struts, and the struts being formed to compensate for the movement of the webs due to the expansion of the head so that the skirt is not distorted by such expansion, and relatively inexpandible cross-struts connecting each web with the adjacent sides of the cross-head slippers.

5 In testimony whereof, I have subscribed my name.
